FRAME FOR A FILM TRANSPARENCY

Heinrich Hrabik, Waldmullergang 10b,
A-4020 Linz, Austria

Filed Feb. 8, 1973, Ser. No. 330,503

Term of patent 7 years

Int. Cl. D16—99

U.S. Cl. D61—1 S

The figure is a top perspective view of a frame for a film transparency showing my new design, the bottom being plain and unornamented.

I claim:

The ornamental design for a frame for a film transparency, as shown and described.
